United States Patent Office.

AUGUSTUS CONRADT, OF PHILADELPHIA, PENNSYLVANIA.

Design No. 4,227, dated July 19, 1870.

DESIGN FOR THE HANDLE OF SPOONS AND OTHER ARTICLES.

The Schedule referred to in these Letters Patent and making part of the same

To all whom it may concern:

Be it known that I, AUGUSTUS CONRADT, of the city of Philadelphia, in the county of Philadelphia and State of Pennsylvania, have originated and designed a new Pattern for a Handle for Spoons, Knives, Forks, &c., and other articles, for table use, of which the following is a full, clear, and exact description.

The handle constitutes the part between the letters A and B, as shown by the drawings.

What I claim as my invention, and desire to secure by Letters Patent, is—

The ornamental design of a handle for spoons, knives, forks, &c., and other articles for table use, as described and shown.

AUGUSTUS CONRADT.
